UNITED STATES PATENT OFFICE.

HARRY E. McKECHNEY, OF ROCHESTER, NEW YORK.

HOSE-NOZZLE.

No. 893,189.

Specification of Letters Patent.

Patented July 14, 1908.

Application filed September 7, 1907. Serial No. 391,813.

To all whom it may concern:

Be it known that I, HARRY E. McKECHNEY, of Rochester, in the county of Monroe and State of New York, have invented a new and 5 useful Improvement in Hose-Nozzles, which improvement is fully set forth in the following specification and shown in the accompanying drawings.

My invention is an improved nozzle for hose, 10 designed more particularly for use with fire engines in the matter of extinguishing fires and for similar purposes.

One object among others in constructing this nozzle is to provide movable coacting 15 parts so arranged that by shifting them a large stream of water of the full capacity of the tip or nozzle proper may be thrown, or a slender stream of small diameter may be discharged through but independent of the tip, 20 a further shifting of the parts also serving to shut off the discharge of water altogether.

Other objects and advantages of the invention will be brought out and made to appear in the following description, and the 25 novel features pointed out in the appended claims, reference being had to the accompanying drawing which, with the reference numerals marked thereon, form a part of this specification.

30 In the drawing Figure 1 is a side view of my improved nozzle with parts shown in various positions by full and dotted lines. Fig. 2 is an elevation of parts at the middle of the device seen as indicated by arrow 35 in Fig. 1, further showing the construction, parts being broken away. Fig. 3 is a view looking into the end of the nozzle. Fig. 4 is a transverse section on the dotted line *a* in Fig. 5, small parts being broken away. Fig.

40 Fig. 5 is a side elevation of the nozzle mainly in central longitudinal section, seen in the direction in which Fig. 1 is seen, parts being shown in two positions by full and dotted lines. Fig. 6 is a transverse section of inner 45 parts on the dotted line *b* in Fig. 5. Fig. 7 is an axial section of parts on the dotted line in Fig. 6, parts being broken away. Fig. 8 is a plan of the base of the axial tube with the upper portion mainly broken away, the 50 barrel being in transverse section and the threaded ring broken away, a part at the left being horizontally sectioned on the dotted line *c* in Fig. 7 to uncover the ring of packing. Fig. 9 is a side elevation of the lower parts of 55 the axial tube, detached, further showing the form, parts being broken away. Figs. 1

and 2 are drawn to a scale smaller than that of the remaining figures.

Referring to the parts shown, 1 in the various figures is the main base portion of 60 the nozzle, internally threaded at its lower end to receive the hose.

2 is the barrel of the nozzle held to have longitudinal motion in the upper end of the base 1.

65 3 is a cap threaded upon the upper end of the base 1 and forming a cover therefor, holding a ring of packing, 4, Fig. 5, to insure a water-tight joint around the barrel 2. The cap 3 is formed with a hexagonal periphery 5 70 for receiving a wrench to turn it, and a divided or branched standard 6, Figs. 1, 2, 4, and 5, at one side of the barrel 2 to which is pivotally hung a U-shaped bail or lever 7, by means of a transverse bolt 8 passing through 75 the ends of the lever and the branches of the standard, a sleeve 29 being placed between the branches. The lever 7 is formed with two opposite inwardly-projecting trunnions 9 9, Fig. 4, extending between two pair of 80 transverse spaced ledges 10 10, Figs. 1, 4 and 5, projecting from the sides of the barrel 2. By means of this construction when the lever 7 is swung one way or the other on the pivot bolt 8 the barrel will be correspondingly 85 moved longitudinally through the upper end of the main base piece 1, these movements of the lever and the barrel being indicated by the dotted-line positions shown in Figs. 1 and 5. The barrel 2 is formed near its upper end 90 with an enlarged part 11 above which it is exteriorly threaded to receive the tip or nozzle proper 12.

95 Within the main base 1 is placed removably a circular rest or holder 13, Figs. 5, 6 and 7, crossing the axis of the base 1 and formed with a ring 14 having its periphery threaded and inserted in a threaded seat 15 in the base 1 above its lower end. This holder 13 has a central body-portion 16 connected with the ring 14 by radial ties 17 leaving spaces 18 for the passage of the water through it into the base 1. The central part 16 has a flange 19 at its upper side forming a shallow cup for holding a disk 20 of packing material upon which the lower open end of the barrel 2 may at times rest. This holder 13 has a central threaded stud 21, clearly shown in Fig. 7, for receiving an internally threaded circular body 22 holding, as a base, 100 a slender tube 23, said tube, the barrel 2 and the main base 1 being coaxial. This inner 105 110

tube base 22 is formed with a circular bottom-portion 24 threaded directly onto the stud 21, and an upper body portion 25 receiving the lower end of the axial tube 23 and being connected with the part 24 by thin radial ties 26 with spaces 27 between for the flow of water into the tube 23. The part 25 of the expanded part or tube base 22 is larger in diameter than the bottom part 24 and meets the inner surface of the barrel 2, a ring 28 of packing material, Figs. 5, 7, 8 and 9, serving to render the joint water-tight between the base 22 and the inner surface of the barrel.

15 The tube base 22 is usually screwed firmly upon the stud 21 of the holder 13 so that said base, the tube 23 and the holder 13 act as a single piece, being inserted into and removed from the main base piece 1 as a single body.

20 And in use the said parts, that is to say, the inner base 22, the tube, the holder and the main base 1 are relatively motionless while the lever 7 and the barrel 2 with the tip 12 may occupy any one of three different positions as may be necessary. That is to say, when the lever is in its lowest position, as appears in full lines in Figs. 1 and 5, the inner end of the barrel 2 will press the packing disk 20, as clearly shown in Figs. 5 and 7, in which

25 position no water can flow through or out of the nozzle, the latter being temporarily out of action. When the lever is at its upper position, shown by dotted lines in Figs. 1 and 5, the barrel and the tip 12 will be extended as shown by the dotted positions in the two figures, the lower end of the barrel being up distant from the disk 20 and forming a full opening into and through the barrel and thus permitting a discharge of water of the full capacity of the exit opening of the tip 12. If, again, the lever be moved to occupy the intermediate position, shown lowest in dotted lines in Fig. 1, the barrel will be only slightly raised from the packing disk 20, as shown by

30 dotted lines in Fig. 9, and sufficient to uncover the openings 27, Figs. 7, 8 and 9, leading into the tube 23 but not sufficient to allow water to pass into the barrel. In this position of the parts a stream of water will

35 flow out of the tube through but independent of the tip 12, the latter being, for the time, idle, for while the barrel is in contact with the part 25 of the tube base 22 and the ring of packing 28 no water can flow into it and the

40 tip 12, the only stream issuing from the nozzle being that delivered through the tube 23. Thus by adjusting the lever 7 the outflowing water may be directed through both the barrel and the tube 23, or through the axial tube

45 23 alone alternately, or wholly stopped.

What I claim as my invention and desire to secure by Letters Patent is:—

1. A hose nozzle comprising a base portion, a barrel held movably by the base portion, a cap for the base portion encircling the

barrel a standard on said cap, a bent lever pivoted to the standard with parts to engage the barrel an inner tube base, a tube carried thereby coaxial with said barrel.

2. A hose nozzle comprising a base portion, a barrel held by the base portion and adapted to move therein, an inner tube base, a tube carried thereby coaxial with said barrel a cap for the base portion encircling the barrel a standard on said cap, and a bent lever joined to the standard, spaced projections on said barrel, and trunnions on the lever extending between said spaced projections.

3. A nozzle for hose, having a base portion, a barrel entering the base portion, a rest within and crossing the axis of the base portion and having openings, an inner tube, and an inner tube base supported upon said rest and means for moving the barrel longitudinally within the base portion toward and from the rest and means for directing the flow of water through the tube or through both the tube and the barrel.

4. A nozzle for hose having a base portion, a barrel held within the base portion, a tube within the barrel a tube base having expanded part and an annular packing and means for directing the flow of water through the tube or through both the tube and barrel.

5. A hose nozzle having a base portion, a barrel held by the base portion, and a tube within the barrel, a tube base having expanded part and an annular packing said base, the barrel and the tube being coaxial, the barrel and the tube being adapted to conduct water, and means for directing the flow of water through the tube or through both the tube and barrel.

6. A hose nozzle having a main base portion, a barrel held movably within the main base portion, and a tube base within the base portion, a tube coaxial with said barrel, there being openings through said tube base communicating between the interior of said base portion and the interior of the tube, and means to move the barrel to open or close said openings.

7. A hose nozzle having a main base, a barrel held movably within the main base, and a tube supported by the main base coaxially within the barrel, an expanded base for said tube touching the inner surface of the barrel within predetermined limits of the movement of the barrel, said tube base having openings communicating between the interior of the main base and the interior of the tube, and means to move the barrel upon said tube base to close or to open said openings.

8. A hose nozzle having a base portion, a barrel with end entering the base portion and longitudinally movable therein, and a tip on the opposite end of the barrel, a tube held centrally within the barrel with its discharge end within the said tip, an inner tube base

having an expanded portion and an annular packing therein and means for moving the barrel to determine the flow of water.

9. A hose nozzle having a base portion, a rest comprising a threaded ring seated in the base portion and a cup - shaped member above said threaded ring, with passage therebetween, a barrel entering the base portion with its end adapted to enter said cup shaped member, a tube within the barrel, a tube base joined to said rest, there being openings

between the rest and said tube base leading into the tube, and means for moving the barrel to control said openings.

In witness whereof, I have hereunto set 15 my hand this 5th day of September, 1907, in the presence of two subscribing witnesses.

HARRY E. McKECHNEY.
